TAPING MACHINE

Filed Sept. 12, 1930

UNITED STATES PATENT OFFICE

WALTER P. OSGOOD, OF MALDEN, MASSACHUSETTS, ASSIGNOR TO BOSTON MACHINE WORKS COMPANY, OF LYNN, MASSACHUSETTS, A CORPORATION OF MASSACHUSETTS

TAPING MACHINE

Application filed September 12, 1930. Serial No. 481,377.

The present invention relates to machines which are used to apply a strip to a piece of sheet material, and more particularly to taping machines which are used in the manufacture of shoes to apply a strip of tape to a shoe upper part.

Such taping machines are usually provided with a support for a piece of sheet material to which the tape is to be applied, means for applying the tape to the material and for feeding the taped material, and means for guiding the tape to the applying means. As the tape is coated with an adhesive on one face and is stored in the machine for use in a coil considerable force must be employed to unwind the tape therefrom. Experience has demonstrated that it is impracticable to rely on the applying means to pull the sticky tape from the coil as the pulling force required causes the tape to drum-head between the applying means and the means for guiding the tape thereto, thus seriously interfering with the ability of the applying means to apply the tape properly to the sheet of material. Heretofore it has been proposed to provide the machine with a separate device for pulling a predetermined length of the tape from the coil in timed relation with the applying means. But as the length of the tape applied to the sheet of material by the applying means varied in accordance with the thickness of successive sheets and as the length of the tape pulled off the coil by the pull-off device was fixed either too short or too long a length of the tape was pulled off the coil thereby. When too little tape was pulled from the coil, the applying means had to make up the deficit, thus causing a portion of the tape to drum-head between the applying means and the means for guiding the tape thereto. When too much tape was pulled from the coil by the pull-off device a loop of slack accumulated which was liable to become entangled in the moving parts of the machine. Analyzing this difficulty, it is apparent that the tension on the tape withdrawn from the source of supply varied.

The principal object of the present invention is to produce a machine of the class described in which the tension on the strip with-

drawn from the source of supply is uniform.

Broadly considered the tension on the strip withdrawn from the source of supply may be maintained uniform by correlating the operations of the pull-off device and the applying means. It is preferred, however, to operate the pull-off so that it draws a longer strip from the source of supply in a single step than the applying means uses up in a single step, and to suspend the operation of the pull-off intermittently to prevent an excessive accumulation.

Other features of the present invention reside in certain devices, combinations and arrangements of parts hereinafter described and then set forth broadly and in detail in the appended claims which possess advantages readily apparent to those skilled in the art.

The various features of the present invention will be understood readily from an inspection of the accompanying drawing illustrating the best form of the invention at present known to the inventor, in which,

Figure 1 is a view in front elevation of a combined seam taping and pressing machine to which the present invention is applied, for the purpose of disclosure, the loop of withdrawn tape being exaggerated to facilitate explanation of the mode of operation;

Fig. 2 is a detail view in perspective of the device for pulling tape from a source of supply and the device for maintaining a uniform tension on the withdrawn tape;

Fig. 3 is a detail view in front elevation showing the pawl located in the orbital path of the pull-off actuating ratchet, and

Fig. 4 is a detail view, similar to Fig. 3, showing how further movement of the ratchet in its orbital path causes the pawl to rotate the ratchet.

The machine herein shown for performing the combined seam-pressing and taping operation is similar in many respects to the taping machine illustrated in my Patent No. 1,691,493, dated November 13, 1928. This patent is provided with a grooved work support in the form of a roll over which the sheet of material to be taped is fed, means to

apply to the sheet an adhesively coated tape, and a presser member which has a movement toward and from the work support and which by such movement applies the tape progressively to the sheet and at the same time feeds the taped sheet forward. Inasmuch as the machine embodying the present invention is similar to that of the patent hereinbefore identified, I have not deemed it necessary to illustrate the complete machine herein, but have shown a sufficient portion thereof to disclose adequately the various features of the present invention.

In Fig. 1 of the drawing 5 designates the roll over which the seamed sheet of material is fed. The tape which is to be applied to the sheet during the seam pressing operation is indicated at 6 and it is illustrated as a strip having one face coated adhesively so that it is normally tacky to cause it to adhere to the seam under pressure.

The pressing of the seam and the applying of the tape thereto are accomplished by the combined action of the work support 5 and a pressing member 7. The pressing member 7 is secured to a head member 8, or lever, which has a vertical movement and also an oscillating movement. The oscillating head 8 is mounted on the main frame 9 of the machine and it receives its oscillating movement from an eccentric 10 on a driving shaft 11 carried by the main frame. The head 8 is provided with a slot 12 through which extends a stud 13 fast on the main frame 9, said stud having a block 14 which is slidably mounted in the slot 12 and is journaled on the stud 13. As the shaft 11 is rotated the eccentric 10 gives the head 8 an up and down movement and also a rocking movement, said movements causing the face of the pressing member 7 to move toward and from the work on the work support and also to have a rocking or rolling contact with the work.

The work is guided into the machine by a resilient seam crease guide 15 and by a seam ridge guide 16. The tape is guided to the work by a tape delivery means 17.

The tape is coiled in a roll 18, constituting the source of supply, which is loosely mounted on a cylindrical support 19 mounted loosely in turn on the stud 20 of a reel 21 carried by an arm 22 rising from the main frame 9. From the coil 18 the tape passes under a flanged drum or roll 23 the milled surface of which engages the sticky face of the tape.

The drum 23 is loosely mounted on a stud 24 which is screwed into the head 8. One face of the drum 23 is provided with a ratchet 25 which is held from movement in a clockwise direction by a pawl 26. The pawl 26 is loosely mounted on a stud 27 secured to a plate 28 (Fig. 1) carried by the stud 24.

The pawl 26 is held engaged with the ratchet 25 by a spring 29, coiled about the stud 24,

one end of which engages the pawl 26 and the other end of which engages the plate 28.

From the drum 23 the tape passes over a take-up roll or feeler 30 which engages the tape on its non-tacky face. The take-up is loosely mounted on a stud 31 projecting laterally from an arm 32 loosely mounted on a stud 33 secured to the main frame 9. From the roll 30 the tape is conducted to the tape delivery means 17 and to the pressing member 7.

From the construction described it is apparent, as the drum 23 is free to rotate in a contra-clockwise direction viewing Fig. 1, that during the feed of the work over the work support 5 by the pressing member 7 there is a tendency for the pressing member to pull tape from the roll 18 at each feeding step. But, as the tacky face of the tape in the coil 18 is stuck to the non-tacky face in an adjacent convolution, considerable force is required to unwind the tape from the coil. It is, therefore, undesirable to rely upon the pressing member 7 to pull tape from the source of supply as the pulling force exerted thereby would drum-head the tape between the work and the tape delivery means 17 and thus interfere with the application of the tape to the work.

In the illustrated embodiment of the present invention the roll 23 is rotated in a manner presently to be described to unwind the tape from the coil 18 and to produce an auxiliary supply of slack tape which is used up as needed by the pressing member 7. Fig. 2 shows the loop of slack tape engaged by the take-up 30. The take-up engages the slack tape under the mild tension of a coiled spring 34 one end of which engages a pin 35 on the arm 32 and the other end of which engages a bracket 36 secured to the main frame 9. Movement of the take-up 30 under the influence of the spring 34 is limited by a screw 37 adjustably secured to the bracket 36.

As the pull-off 23 is mounted on the head 8 the pull-off ratchet 25 moves in an orbital path during the vertical reciprocation and lateral oscillation of the head 8. In order to rotate the pull-off 23 during these movements of the head the stud 33 loosely carries a pawl 38. As shown in Fig. 2 the hubs of the arm 32 and the pawl 38 interfit, there being a space between the hubs to allow the take-up 30 and the pawl 38 to move relatively. Coiled about the hubs of the arm 32 and the pawl 38 is a spring 39 one end of which engages the arm 32 and the other end of which engages the pawl 38.

Fig. 2 shows the pawl 38 withdrawn from the orbital path of the ratchet 25. This is due to the position of the take-up or feeler 30 which is held in engagement with the loop of withdrawn tape by the light spring 34. In consequence no tape is pulled from the source

of supply by the roll 23 which is stationary during the operation of the tape applying and seam pressing member 7. As the slack in the loop of withdrawn tape engaged by the 5 take-up 30 is used up by the pressing member 7 the take-up 30 is moved by the tape against the light tension of the spring 34 until the pawl 38 is moved into the orbital path of the ratchet 25, as shown in Fig. 3, when the pawl 10 38 engages a tooth in the ratchet 25. Then as the ratchet 25 continues to move downwardly and laterally the pawl 38 rotates the ratchet 25 and the roll 23 to draw tape from the coil 18. During the movement of the ratchet 25 15 in engagement with the pawl 38 the spring 39 enables the pawl 38 to yield relatively to the take-up 30. Thus, rotation of the pull-off 23 does not increase the tension of the take-up 30 on the tape engaged thereby.

20 In order to prevent the ratchet 25 from riding over the pawl 38 during the movement of the head 8 the bracket 36 carries an adjustable screw 40 which limits the movement of the pawl 38 into the orbital path of the ratchet 25.

25 In order to control the pull-off stroke of the pull-off 23 the pawl 38 is made in two parts 41 and 42 so that they may be adjusted longitudinally through the screw and slot connection 43. The selected adjusted position of the parts 41 and 42 is maintained by a drift 44, herein shown as a wedge block, interposed between the head of the pawl 38 and one end 30 of the part 41.

35 In the illustrated embodiment of the invention the stroke of the pull-off 23 is such that more tape is pulled from the coil 18 in a single stroke thereof than is used up by the pressing member 7 in a single feeding step thereof. With such a construction and mode of operation the withdrawn tape is bound to accumulate. But as the spring 34 maintains the 40 take-up 30 engaged with the withdrawn tape during its accumulation the pawl 38 is withdrawn from the orbital path of the ratchet 25 and the operation of the pull-off 23 suspended. When the pressing member 7 eats into the accumulation of withdrawn tape the 45 pawl 38 is replaced in the orbital path of the ratchet 25 and the pull-off 23 is rotated again to withdraw more tape. In the preferred mode of operation the pull-off 23 operates in timed relation with the pressing member 50 55 7 during successive cycles varying in number depending upon prevailing conditions and then the operation of the pull-off 23 is suspended for one cycle, or, it may be, successive cycles, depending again on the prevailing 60 conditions. Thus, while the pressing member 7 is operated periodically the pull-off 23 is operated non-periodically.

65 It will be apparent to those skilled in the art that with this construction and mode of operation the tension on the tape, between the

pull-off 23 and the pressing member 7, herein called the withdrawn tape, is uniform notwithstanding variations in the length of tape applied to the work by the pressing member.

70 Nothing herein explained is to be interpreted as limiting the various features of the present invention in the scope of its application to use in connection with the particular machine or the particular mode of operation or both selected for purposes of illustration and explanation. While the particulars of construction herein set forth are well suited to one mechanical form of the invention and to the use to which it is put, it is not limited to this use, nor to these details of construction, nor to the conjoint use of all its features, nor is it to be understood that these particulars are essential since they may be modified within the skill of the artisan without departing from the true scope of the actual invention, characterizing features of which are set forth in the following claims by the intentional use of generic terms and expressions inclusive of various modifications.

75 80 85 What is claimed as new, is:

1. A machine of the class described having, in combination, a support for a piece of sheet material to which a reinforcing strip is to be applied, means for applying the strip to the material and for feeding the reinforced material, and means for maintaining a uniform tension on the strip during its application and feed.

90 95 100 105 2. A machine of the class described having, in combination, a support for a piece of sheet material to which a reinforcing strip is to be applied, means for applying the strip to the material and for feeding the reinforced material, a pull-off for drawing the strip from a source of supply, and means for maintaining a uniform tension on the withdrawn strip.

110 115 3. A machine of the class described having, in combination, a support for a piece of sheet material to which a reinforcing strip is to be applied, means for applying the strip to the material and for feeding the reinforced material, a pull-off for drawing the strip from a source of supply, and means for maintaining a uniform tension on the withdrawn strip between the pull-off and the applying and feeding means.

120 4. A machine of the class described having, in combination, mechanism for drawing a strip of material from a source of supply, mechanism for using up the withdrawn strip, and means for operating said mechanisms non-periodically and periodically, respectively.

125 130 5. A machine of the class described having, in combination, mechanism for drawing a strip of material from a source of supply, mechanism for using up the withdrawn strip, and means controlled by the withdrawn strip

for operating the strip drawing mechanism non-periodically.

6. A machine of the class described having, in combination, mechanism for drawing a strip from a source of supply, mechanism for using up the withdrawn strip, and a withdrawn strip take-up mechanism for operating the strip drawing mechanism non-periodically.

10. 7. A machine of the class described having, in combination, mechanism for drawing a strip from a source of supply, mechanism for using up the withdrawn strip, a device for maintaining the withdrawn strip under tension, and means controlled by said device for operating the strip drawing mechanism non-periodically.

8. A machine of the class described having, in combination, mechanism for drawing a strip from a source of supply and for producing an auxiliary source of supply, mechanism for using up the withdrawn strip in the auxiliary source of supply, and means controlled by the strip in the auxiliary source of supply for throwing the strip drawing mechanism into and out of operation.

9. A machine of the class described having, in combination, mechanism for drawing a strip from a source of supply, mechanism for using up the withdrawn strip, said mechanism operating in a step by step manner, the first named mechanism drawing a longer strip in a single step than the second named mechanism uses up in a single step, and mechanism for suspending the operation of the first named mechanism intermittently.

10. A machine of the class described having, in combination, mechanism for drawing a strip from a source of supply, mechanism for using up the withdrawn strip, said mechanisms operating in a step by step manner, the first named mechanism drawing a longer strip in a single step than the second named mechanism uses up in a single step, and mechanism for determining the time of operation of the first named mechanism.

11. A machine of the class described having, in combination, a roll engaged with the sticky face of a strip of reinforcing material for drawing it from a source of supply, mechanism for using up the withdrawn strip, and means for determining the time of operation of the roll.

12. A machine of the class described having, in combination, a roll engaged with a sticky face of a strip of reinforcing material for drawing it from a source of supply, mechanism for using up the withdrawn strip, and means engaged with the withdrawn strip for separating the strip from the roll and for determining the time of operation of the roll.

13. A taping machine having, in combination, a roll for drawing tape from a source of supply, a ratchet for rotating the roll, mechanism for moving the roll and ratchet in a

path, mechanism for using up the withdrawn tape, a feeler engaged with the withdrawn tape and a pawl controlled by the feeler, the feeler acting when the supply of withdrawn tape is low to move the pawl into the path of the ratchet.

14. A taping machine having, in combination, a roll for drawing tape from a source of supply, a ratchet for rotating the roll, mechanism for moving the roll and the ratchet in an orbital path, mechanism for using up the withdrawn tape, a feeler engaged with the withdrawn tape and a pawl controlled by the feeler, the feeler acting when the supply of withdrawn tape is low to move the pawl into the path of the ratchet.

15. A taping machine having, in combination, a roll for drawing tape from a source of supply, a ratchet for rotating the roll, a pawl movable into and out of engagement with the ratchet, a feeler engaged with the withdrawn tape for controlling the movement of the pawl, and mechanism for relatively moving the ratchet and the pawl engaged therewith.

16. A taping machine having, in combination, an operating tool, a lever mounted and actuated to impart a four-motion operation thereto, a roll for drawing tape from a source of supply mounted on the lever, a ratchet for rotating the roll, a pawl mounted independently of the lever movable into and out of engagement with the ratchet, and a feeler engaged with the withdrawn tape for controlling the movement of the pawl.

17. A taping machine having, in combination, mechanism for drawing tape from a source of supply and producing a loop of slack tape, a feeler engaged with the loop, mechanism for using up the withdrawn tape and thereby reducing the size of the loop, means controlled by the feeler for operating the tape drawing mechanism to produce more slack in timed relation with the mechanism for using up the withdrawn tape, and means for causing the feeler to maintain its engagement with the loop as it lengthens and stop further withdrawal of the tape from the source of supply.

18. A taping machine having, in combination, a moving lever, a roll mounted thereon, a ratchet for rotating the roll, a pawl mounted independently of the lever, and means for moving the pawl into engagement with the ratchet whereby movement of the lever causes the pawl to operate the ratchet.

19. A taping machine having, in combination, a lever, a pivot therefore, means for oscillating the lever on its pivot and for reciprocating the pivot, a roll mounted on the lever, a ratchet for rotating the roll, a pawl mounted independently of the lever, and means for moving the pawl into engagement with the ratchet whereby the combined oscillating and reciprocating movements of

the lever causes the pawl through the ratchet to rotate the roll.

20. A machine of the class described having, in combination, a support for a piece of sheet material to which a reinforcing strip is to be applied, means for applying the strip to the material and for feeding the strip and the material, and positive means for pulling off a longer length of strip from a source of supply than is fed by the applying and feeding means.

In testimony whereof I have signed my name to this specification.

WALTER P. OSGOOD.
